UNITED STATES PATENT OFFICE.

FRED MATHEWS, OF CHICAGO, ILLINOIS, ASSIGNOR TO CLINTON C. MURPHY, OF CHICAGO, ILLINOIS.

CAR-DOOR.

1,244,626.

Specification of Letters Patent. Patented Oct. 30, 1917.

Application filed September 20, 1915. Serial No. 51,538.

To all whom it may concern:

Be it known that I, FRED MATHEWS, a citizen of the United States, residing at Chicago, in the county of Cook and State of Illinois, have invented new and useful Improvements in Car-Doors, of which the following is a full, clear, and exact description.

My invention relates to improvements in car doors, and its object is to provide a door which is partly hung from above and partly supported below, and when closed is held in position by an overhead trolley at its front end and by an antifriction roller under its rear end, and to avoid the necessity for anti-friction rollers in the guide-brackets below the sill of the doorway where the freight being loaded or unloaded through the doorway is liable to injure them and cause them to seriously interfere with the sliding movement of the door. This I accomplish by the means hereinafter fully described, and as particularly pointed out in the claims.

In the drawings:

Figure 1 is a side elevation of the central portion of a box car showing a sliding door embodying my improvements.

Fig. 2 is a vertical section of a fragment of the same taken on dotted line 2—2, Fig. 1, and drawn to a larger scale.

Referring to the drawings A represents a box-car having a suitable doorway, the frame of which projects beyond the side of the car, and the lintel *a* of which has resting upon the projecting portion thereof an angle iron track *b*, the vertical web of which is secured to the side of the car by bolts *c* or otherwise. The doorway is closed by a suitable door *B* which may be of any suitable construction, but I prefer to use a door whose edges are bound by metal and whose upper and lower edges are protected by *Z*-bars *D* and *d*, respectively. *Z*-bar *D* protecting the upper edge of door *B* has its outer flange lapping down over the outer vertical surface thereof, and the web connecting its flange resting upon the top edge of the door and projecting inward toward the side of the door a distance practically corresponding to the extent of the projection of lintel *a*. The inner flange of this *Z*-bar *D* projects upward back of the lower depending portion of a guide-plate *E* whose upper portion is secured to the fascia *e* of the car and holds the upper portion of the door

in operative position against the side of the car. The rear end of *Z*-bar *D* has the upper flange thereof offset obliquely outward to form a cam surface *f*, and when the door is closed this cam surface *f* engages and opposes a cam surface *g* made by pushing the lower edge of the guide-plate obliquely inward toward the side of the car, substantially as shown in the drawings.

The lower edge of the door, when open, is supported by antifriction wheels *h* of brackets *G*, which latter are constructed similar to those for which Letters Patent of the United States were granted to me August 3, 1915, No. 1,148,607, and when the door is closed its rear end is supported by the roller of the bracket nearest the doorway and the opposite end thereof is suspended by means of an overhead trolley *I*, which is journaled upon a stud *H* projecting from a suitable screw-plate *K* secured to the inner side of the door near the upper corner thereof nearest jamb *F*. This trolley-wheel travels upon a horizontal flange of the angle-iron track *b* and sustains the forward edge of the door unaided and continues to do so until the door is moved toward its open position far enough for its lower edge to engage and be supported by the intermediate anti-friction-wheel brackets *G*. The horizontal web of *Z*-bar *d* forms a tread for the lower edge of the door and engages wheels *h* as the door moves back and forth. The downwardly projecting flange of this *Z*-bar *d* depends back of said wheel *h* and holds the lower edge of the door in position against the car. Immediately beneath the sill of the doorway and between bracket *G* and the jamb of the doorway two substantially *Z*-shaped retaining brackets *k* are secured to the side of the car, and the outer upwardly projecting flange of these brackets extends upward in front of the lower edge of the door and holds the door closed, but these brackets *k* do not support the door unless wheel *I* should break while the door is in its closed position. These retaining brackets *k* are not as liable to become injured when the door is open by the freight being loaded into the car, or removed therefrom.

What I claim as new is:

1. A car having a doorway the frame of which projects beyond the side of the car, a metal track mounted upon and secured to projecting portion of the lintel of said

frame, a fascia above said lintel, and a guide-plate secured to the outer surface of and projecting down below said fascia, in combination with a sliding door which is unsupported below said doorway, a Z-bar the web of which is secured to the upper edge of said door and projects inward beyond the inner side thereof and the uppermost flange of which projects upward from the back of the depending portion of said guide-plate, a wheel suitably journaled to and projecting from the inner side of said door near the upper forward corner of the same which travels in said track, and brackets secured to the side of the car under and to the rear of the rear side of the door and in a horizontal plane below the door which support said door when it is open.

2. A car having a doorway the frame of which projects beyond the side of the car, a fascia, a guide-plate secured to the outer surface of and having its lower edge de-

pending below said fascia, in combination with a sliding door which is unsupported below said doorway, a wheel suitably journaled to the inner side of said door near the upper forward corner of the same, a Z-bar the web of which is secured upon the upper edge of said door and projects inward beyond the inner side of the door and has the uppermost flange thereof projecting up from the inner edge of said Z-bar back of said guide-plate, and brackets secured to the side of the car under and to the rear side of the door and in a horizontal plane below the door which support said door when it is open.

In witness whereof I have hereunto set my hand this 14th day of September, 1915.

FRED MATHEWS.
